UNITED STATES PATENT OFFICE.

JOHN J. MAXWELL, OF WASHINGTON, DISTRICT OF COLUMBIA.

HAMMOCK.

No. 909,102.

Specification of Letters Patent.

Patented Jan. 5, 1909.

Application filed September 10, 1908. Serial No. 452,388.

To all whom it may concern:

Be it known that I, JOHN J. MAXWELL, a citizen of the United States, and a resident of Washington, in the District of Columbia, 5 have made certain new and useful Improvements in Hammocks, of which the following is a specification.

My invention relates to improvements in hammock frames and it consists in the combinations, constructions and arrangements of parts herein described and claimed.

An object of my invention is to provide a frame for a hammock which will keep the hammock spread apart in the most convenient position for the user and at the same time will permit the hammock to adjust itself automatically to persons of different weights who occupy the hammock without any danger of breaking or straining of the frame 20 structure.

A further object of my invention is to provide a frame and covering for a hammock which will permit the occupant of the hammock to swing backward and forward without straining or otherwise injuring the frame or its covering.

A further object of my invention consists in the provision of a collapsible frame which may be taken down and packed away in 30 small compass for transportation, thus rendering the device of a portable nature.

Other objects and advantages will appear in the following specification and will be more particularly pointed out in the annexed 35 claims.

My invention is illustrated in the accompanying drawings in which—

Figure 1 is a side view of the hammock embodying my invention; Fig. 2 is a sectional view along the line 2—2 of Fig. 1, looking in the direction of the arrow; Fig. 3 is a plan view showing a hammock and the means for suspending it; Fig. 4 is a sectional view of a portion of the hammock and frame along the 45 line 4—4 of Fig. 3; Fig. 5 is an enlarged detail sectional view of the sliding bolt; and Fig. 6 is a detail view showing the central connection of the side frame members.

Referring now to Fig. 1, I have shown 50 therein a supporting frame consisting of the base members 1, the inclined uprights 2 and 3 at either end thereof, the latter being braced by the corner braces 2' and 3' respectively. Between the uprights 2 and 3 55 and their corresponding uprights on the opposite sides, are the cross members 4. The

cross members 4 besides acting as braces for the supporting frame constitute attaching members for the hammock and are provided with a series of hooks 5 arranged therealong 60 to provide means for shifting the position of the hammock from one side to the other.

The hammock frame proper consists of the grooved side pieces 6, which are preferably in two sections having their ends off-set in the 65 manner shown in Fig. 6, and secured by bolts thus forming one continuous piece, together with the end pieces 7. The side pieces 6 and the end pieces 7 are preferably made of light steel or iron strips of L shaped cross section as clearly shown in the figures. These strips are secured to each other by means of small bolts.

The hammock itself which may be of ordinary coarse fiber, canvas, wire or any other suitable material is preferably of a rectangular shape and of a size to just fit inside of the frame formed by the pieces 6 and 7. The hammock is attached at each of its four corners to sliding bolts denoted in general by 8. The latter consists of two separate parts as shown in Fig. 5. One of these parts 8^a is provided with an eye on one end and has a threaded bore in the other end. The other 8^b is provided with a similar eye and has an externally threaded shank arranged to be screwed into the bore of the first mentioned part. The bolts 8 are arranged to pass through holes 9 in the end members 7, and the uprights 10. A number of these holes 9 90 is provided in order to permit the adjustment of the hammock at various heights. The holes 9 are reamed out on either side as clearly shown in Fig. 5 for a purpose herein-after set forth.

Referring again to Fig. 1, it will be seen that upright members 10 on the opposite sides of the hammock frame are connected by the cross pieces 11 at their tops. A short upright supporting member 12 is arranged 100 on each one of the cross members 11 to provide a slight pitch for the protecting covering 13. The latter may be canvas or any other water-proof or durable material and may be either located in the top of the frame 105 or may extend all around the sides thereof. A convenient arrangement for taking the canvas covering off and for putting it on is to provide buttons similar to those used on carriage tops for attaching the various portions of the covering. The hammock as thus described is suspended from the end sup-

ports 4 by means of the ropes or wires 14 which are attached at the lower end to the eye in the part 8^a of the bolt 8.

Having thus described the various parts 5 of the device the operation thereof can be easily understood. It will be seen that I have provided a light rectangular frame the end pieces of which constitute a spreader and permit the suspension of the hammock by 10 means of the sliding bolts 8. In using the hammock, the parts 8^a and 8^b are screwed together until the hammock proper is somewhat above the side members 6. The weight of the occupant of the hammock will 15 cause the latter to assume practically the same position as that shown by the side members in Fig. 1. In doing this, the tension will cause the bolts 8 to slide through the openings and automatically adjust them- 20 selves according to the weight of the occupant. In order to permit a ready adjustment I ream out each side of the holes 9 so that the bolts may take an inclined position with respect to the end members. There is 25 sufficient resiliency in the frame to cause it to give slightly but it will not be permanently sprung out of its normal position because the weight of the occupant does not come upon it but rather is borne by the uprights 30 through the ropes 14. Since the covering support is connected directly to the lower rectangular frame constituting the spreading member there is very little strain such as would be present if the sides of the hammock 35 were attached directly to the frame itself and consequently the motion of the hammock will cause very little strain and no injury to the covering frame itself.

One objection to the use of an ordinary 40 hammock is that unless the supports to which the hammock is attached are at a suitable distance apart the hammock will have too great a curve when it is occupied, thereby bringing the head and feet on an 45 incline instead of in a horizontal position. It will be seen that my device obviates this difficulty since the frame provides a spreader and at the same time permits the hammock to adjust itself to the weight of the occupant 50 while being spread to its utmost limit.

My device may be used to advantage on camping or outing trips. It may be taken apart by the removal of the bolts which connect the various parts of the framework and 55 can be transported in small bulk. I contemplate the use of screens which may extend all around the upright framework and underneath the rectangular framework constituting the spreader. It is obvious that other

forms of the device based upon the same 60 general idea may be made, but I consider as my own and desire to claim all such modifications as clearly fall within the spirit and scope of the invention.

While I have shown the hammock as sup- 65 ported by the inclined uprights constituting part of the framework, it will be understood that the hammock may be suspended from any suitable supports and that the main invention lies in the provision of the adjustable 70 spreading frame, rather than in the supports themselves, and that the invention is designed to be used with stationary supports, such as the posts of a porch, or trees, or any other suitable suspending means. 75

In order to provide for the suspension of a hammock of the ordinary form I may make use of a bar which is provided with shouldered ends adapted to enter the openings in the rings 8^b and which may have on their threaded ends nuts for preventing the displacement of the bar. These nuts are not absolutely necessary, but may be used if thought desirable. I may provide a series of hooks along the bar, or holes, for the attachment of the suspending ropes. When the hammock is used, the weight of the occupant causes a simultaneous movement of the bar and the slideable bolts. 80

I claim:

1. The combination with a hammock, of a bottom frame therefor constituting a spreader, a support, a series of bolts attached to said hammock and arranged to slide through openings in said spreader frame, and means for securing said bolts to said support. 90

2. The combination with a hammock, of a frame constituting a spreader and composed of light metallic members of L-shaped cross section, a protecting covering carried by said frame, adjustable bolts disposed in openings in said frame, means for attaching the hammock to one end of said bolts and suspending means attached to the other end of said bolts. 100

3. The combination with a hammock, of a bottom frame therefor constituting a spreader, a rigid protecting frame carried by said bottom frame, and arranged to receive a cover, supporting means for said hammock movable relatively to said bottom frame, and means for adjusting the length of supporting means intermediate of the points of attachment. 110

JOHN J. MAXWELL.
